US00D641909S

(12) **United States Design Patent**
Johnson

(10) **Patent No.:** **US D641,909 S**
(45) **Date of Patent:** **** Jul. 19, 2011**

(54) **FIRE RATED DOWNLIGHT HOUSING**

(75) Inventor: **Andrew Joseph Johnson**, Gerrards Cross (GB)

(73) Assignee: **Aurora Lighting, Inc.**, Clearwater, FL (US)

(**) Term: **14 Years**

(21) Appl. No.: **29/352,831**

(22) Filed: **Dec. 28, 2009**

Related U.S. Application Data

(62) Division of application No. 29/330,675, filed on Jan. 12, 2009, now Pat. No. Des. 624,688.

(51) **LOC (9) Cl.** **26-05**

(52) **U.S. Cl.** **D26/74**

(58) **Field of Classification Search** D26/72, D26/74-76, 78, 118, 120; 362/147-148, 362/365-366, 373

See application file for complete search history.

(57) **CLAIM**

The ornamental design for a fire rated downlight housing, as shown and described.

DESCRIPTION

FIG. 1 is a top plan view of a fire rated downlight housing, showing my new design;
FIG. 2 is a bottom plan view thereof;

FIG. 3 is a perspective view from the top;

FIG. 4 is a perspective view from the bottom;

FIG. 5 is an end view thereof from one end;

FIG. 6 is a side elevational view thereof;

FIG. 7 is a top plan view of a first alternative embodiment of a fire rated downlight housing, showing my new design;

FIG. 8 is a bottom plan view thereof;

FIG. 9 is a perspective view from the top;

FIG. 10 is a perspective view from the bottom;

FIG. 11 is an end view thereof from one end;

FIG. 12 is a side elevational view thereof;

FIG. 13 is a top plan view of a second alternative embodiment of a fire rated downlight housing, showing my new design;

FIG. 14 is a bottom plan view thereof;

FIG. 15 is a perspective view from the top;

FIG. 16 is a perspective view from the bottom;

FIG. 17 is an end view thereof from one end;

FIG. 18 is a side elevational view thereof;

FIG. 19 is a top plan view of a third alternative embodiment of a fire rated downlight housing, showing my new design;

FIG. 20 is a bottom plan view thereof;

FIG. 21 is a perspective view from the top;

FIG. 22 is a perspective view from the bottom;

FIG. 23 is an end view thereof from one end;

FIG. 24 is a side elevational view thereof;

FIG. 25 is a top plan view of a fourth alternative embodiment of a fire rated downlight housing, showing my new design;

FIG. 26 is a bottom plan view thereof;

FIG. 27 is a perspective view from the top;

FIG. 28 is a perspective view from the bottom;

FIG. 29 is an end view thereof from one end;

FIG. 30 is a side elevational view thereof;

FIG. 31 is a top plan view of a fifth alternative embodiment of a fire rated downlight housing, showing my new design;

FIG. 32 is a bottom plan view thereof;

FIG. 33 is a perspective view from the top;

FIG. 34 is a perspective view from the bottom;

FIG. 35 is an end view thereof from one end; and,

FIG. 36 is a side elevational view thereof.

The broken lines illustrate environmental components of the fire rated down light housing which form no part of the claimed design.
